W. WHITE

Des. 157,651

TIE HOLDER OR SIMILAR ARTICLE

Filed Jan. 21, 1948

FIG. 2

FIG. 3

FIG. 4

INVENTOR.
WILLIAM WHITE
BY Leon M. Straus A.T.

UNITED STATES PATENT OFFICE

157,651

TIE HOLDER OR SIMILAR ARTICLE

William White, Providence, R. I.; John T. Keenan, trustee in bankruptcy of said William White, assignor to Samuel Jacobs, Cranston, R. I.

Application January 21, 1948, Serial No. 143,924

Term of patent 14 years

(Cl. D17—10)

To all whom it may concern:

Be it known that I, William White, a citizen of the United States of America and residing at Providence, county of Providence, State of Rhode Island, have invented a new, original, and ornamental Design for a Tie Holder or Similar Article, of which the following is a specification, reference being made to the accompanying drawing, forming part thereof.

Fig. 1 is a front view of a tie holder or similar article showing my new design;

Fig. 2 is a rear view thereof;

Fig. 3 is a top view thereof; and

Fig. 4 is a top view showing the loop-shaped features in a locked position.

I claim:

The ornamental design for a tie holder or similar article, substantially as shown and described.

WILLIAM WHITE.
